CLAIM

The ornamental design for a dual spike insert for dispensing liquid from a bag, as shown and described.

DESCRIPTION

FIG. 1 provides a perspective view of a dual spike insert for dispensing liquid from a bag.

FIG. 2 provides a top view of a dual spike insert for dispensing liquid from a bag.

FIG. 3 provides a bottom view of a dual spike insert for dispensing liquid from a bag.

FIG. 4 provides a front view of a dual spike insert for dispensing liquid from a bag.

FIG. 5 provides a rear view of a dual spike insert for dispensing liquid from a bag.

FIG. 6 provides a right side view of a dual spike insert for dispensing liquid from a bag.

FIG. 7 provides a left side view of a dual spike insert for dispensing liquid from a bag; and,

FIG. 8 provides a perspective view of a dual spike insert for dispensing liquid from a bag as it would be inserted into a bag supporting apparatus.

The broken lines showing a bag supporting apparatus used in conjunction with the dual spike insert for dispensing liquid from a bag are for illustrative purposes only and form no part of the invention. The short broken lines projecting from the dual spike insert and down into the bag supporting apparatus are used to show the direction of placement and form no part of the claimed design.
